UNITED STATES PATENT OFFICE.

DANIEL P. ROBINSON, OF BALTIMORE, MARYLAND, ASSIGNOR TO CONTINENTAL CAN COMPANY, OF BALTIMORE, MARYLAND, A CORPORATION OF NEW JERSEY.

METHOD OF CUTTING DISKS.

No. 915,043.

Specification of Letters Patent. Patented March 9, 1909.

Application filed January 28, 1909. Serial No. 474,766.

To all whom it may concern:

Be it known that I, DANIEL P. ROBINSON, a citizen of the United States, residing at Baltimore, in the State of Maryland, have 5 invented certain new and useful Improvements in Methods of Cutting Disks, of which the following is a description, reference being had to the accompanying drawing, and to the letters and figures of reference marked 0 thereon.

My invention relates to new and useful improvements in the methods of cutting disks from sheets of metal with a gang of dies, and has for an object to cut in successive operations a maximum number of disks 5 from a sheet by the esamt arrangement of dies.

I have shown and described in my co-pending application, Serial No. 422,225, filed March 20th, 1908, an apparatus including an 0 arrangement of dies and gage pins, wherein my improved method hereinafter described may be carried out.

In the drawings, which show by way of illustration an application of my method, the arrangement of disks and the arrangement of the sheet and the disks in the different steps of the method,—Figure 1 represents a sheet of metal from which, by a suitable gang of dies, disks have been cut, in accordance with one step of my method; Fig. 2 is a similar view, showing the sheet shifted laterally, and a series of disks cut therefrom by another step of my method; Fig. 3 is a view similar to Fig. 1, showing the sheet changed end for end, and positioned so that a series of disks may be cut therefrom by another step 0 in my method; Fig. 4 is a view similar to Fig. 3, showing the sheet shifted laterally, and a series of disks cut therefrom by another step 0 in my method.

In carrying out my method, a sheet of metal 1 is presented to a gang of dies, which, as herein illustrated, are twelve in number, and so disposed relative to one another, that 5 a series of disks *a* are cut from said sheet of metal. The twelve disks, as shown in Fig. 1, are arranged in three parallel rows indicated by dotted lines 2—2, 3—3 and 4—4. The disks are disposed in each row, so that the distance between said disks indicated by the letter *x* is slightly greater than the diameter of one of the dies, so that in another operation, either subsequent or prior to the above operation, a disk may be cut from the sheet 10 of metal by one of said gang of dies, which

will be located between the adjacent disks in each row.

The end disk 5 in each row is preferably located adjacent the ends of the sheet; that is, said disk is disposed only such distance 60 from the edge of the sheet as to allow the material from which the disk is being cut, to hold together at this point. The end disk 6 in each row is spaced from the other edge of the sheet a distance slightly greater than 65 half the diameter of one of the dies, for the purpose hereinafter described.

The rows 2—2, 3—3, and 4—4 are spaced a distance from one another slightly less than the diameter of the dies, so that in another 70 operation, either subsequent or prior to the above operation, a row of disks may be cut from the sheet of metal, by the same gang of dies, which row is disposed between the adjacent rows above described, provided 75 that the disks in said row are staggered relative to the disks in the first named rows. The row of disks 4—4 is also preferably arranged a distance from the edge of the sheet, so as to allow another row of disks to be cut 80 from said sheet by the same gang of dies between the row 4—4 and the edge of the sheet, provided the disks are staggered relative to the disks in the row 4—4.

In another operation, the sheet of metal 85 is shifted laterally, so as to position said sheet relative to said gang of dies, whereby a series of disks *b*, which, as herein illustrated, are nine in number, are cut from said sheet. Said series of disks are arranged in 90 the rows 2—2, 3—3 and 4—4, and are located between the disks in said rows.

In another operation, the sheet of metal is changed end for end, and presented to said 95 gang of dies, so that a series of disks *c* are cut therefrom. Said disks *c* are arranged in three parallel rows 7—7, 8—8 and 9—9. The row 7—7 is located between the rows 2—2 and 3—3 of the first named series of disks, while the row 8—8 is between the rows 3—3 and 4—4, and the row 9—9 is between the row 4—4 and the edge of the sheet. The end disks 10 in each of the rows of said 100 series of disks are preferably located adjacent the edge of the sheet 11, which is the opposite end of the sheet adjacent which the disks 5 are located. The end disks 6 of the first series of disks are spaced a sufficient distance from the edge 11 of the sheet, so as to provide sufficient metal for cutting the end 105 110

disk 10. The disks *c* in each row are staggered relative to the disks in the adjacent rows. The disks *c* in each row are also located a distance, indicated by *y* in the drawing, from one another, which is slightly greater than the diameter of the dies, whereby in a subsequent or in a prior operation, a disk may be cut from the sheet of metal between the said adjacent disks *c*.

10 In another operation, the sheet of metal is shifted laterally, and a series of disks *d*, as herein illustrated, nine in number, are cut by said gang of dies. The disks *d* are located in the rows 7—7, 8—8 and 9—9, and 15 between the disks *c*.

It is well understood that in cutting disks from a sheet of metal, it is impracticable to cut two disks from the metal at the same time, which shall be very close to each other, 20 for the reason that the female dies which coöperate with the male dies must be necessarily spaced a sufficient distance, in order to provide sufficient metal to form a female die.

25 By my improved method, the disks which are cut in any one operation, are spaced a sufficient distance, so that in another operation a disk may be cut from the metal between the first mentioned disks, and, therefore, 30 in the separate operations, I am enabled to cut disks from a sheet of metal which are spaced only a sufficient distance to allow the metal to hang together and thereby reduce to a minimum the waste material in each sheet which is being cut.

It will further be noted that by my improved method, each operation may be performed by the same gang of dies, the sheet merely being shifted laterally relative to the 40 gang of dies, and changed end for end, and properly positioned so as to cut the different arrangements of disks above described.

It will be obvious that the various steps of my method may, if desired, be performed in a different order from that herein described. That is to say, the second series of disks may be cut prior to the first series of disks, or any order of cutting may be followed.

I have herein referred to the preferred 50 order of cutting the disks, solely as a means of describing the location of one series of disks relative to another, and the location of the sheet relative to the gang of dies.

Having thus particularly described my 55 invention, what I claim as new and desire to secure by Letters Patent, is:—

The method of cutting disks from a sheet of metal, consisting in cutting in one operation by a gang of dies, a series of disks arranged in parallel rows with the space between adjacent disks slightly greater than the diameter of the dies and the space between the rows of disks slightly less than the diameter of the dies, shifting the sheet laterally and cutting in another operation by said gang of dies, a series of disks located between the disks and in the rows of the first named series, changing the position of the sheet end for end, and cutting in another operation 70 by said gang of dies, a series of disks located in parallel rows between the rows of the first named series and staggered relative to the disks in said rows, and shifting the sheet laterally and cutting in another operation by 75 said gang of dies a series of disks located between the disks and in the rows of the last named series.

In testimony whereof I affix my signature, in presence of two witnesses.

DANIEL P. ROBINSON.
